UNITED STATES PATENT OFFICE.

BENJAMIN F. EMERY, OF JONES TOWNSHIP, UNION COUNTY, IOWA.

WIRE MENDING AND FENCE TOOL.

Application filed March 27, 1922. Serial No. 547,097.

To all whom it may concern:

Be it known that I, BENJAMIN F. EMERY, a citizen of the United States of America, and resident of Jones Township, Union 5 County, Iowa, have invented a new and useful Wire Mending and Fence Tool, of which the following is a specification.

The object of this invention is to provide an improved tool adapted for use in stretching wires, applying splice wires to strand wires, attaching and stretching splice wires relative to strand wires, applying stays to strand wires, and making stays of various kinds.

15 A further object of this invention is to provide an improved construction for a tool adapted for manual actuation in stretching, splicing and twisting wires.

My invention consists in the construction, 20 arrangement and combination of elements hereinafter set forth, pointed out in my claims and illustrated by the accompanying drawing, in which—

Figure 1 is an elevation showing a section 25 of fence of conventional form to which various stays and repairs are applied and which illustrates the use of my improved tool.

Figure 2 is a side view of my improved 30 tool, a portion of one end being broken away, on an enlarged scale relative to the showing in Figure 1. Figure 3 is an elevation of one end and Figure 4 an elevation of the opposite end of the tool shown in 35 Figure 2.

Figure 5 is a plan illustrating the use of my improved tool in the manufacture of a wire fence stay.

Figure 6 is a plan illustrating the use of 40 my improved tool in the manufacture of a cored wire fence stay particularly adapted for use as a lightning-rod or electrical conductor.

In the construction of the device as shown 45 the tool consists primarily of a single piece of bar metal, circular in cross-section and of substantially uniform diameter from end to end, said piece of bar metal being formed with a crank 10 between its ends, having its 50 end portions in longitudinal alignment whereby a brace, designated generally by the numeral 11, is produced. The crank 10 is formed with a longitudinal slot 12 in its central portion adapted to receive one or 55 more wires for the purpose of twisting said wires upon each other or upon some other

object through and by reason of manipulation of the tool. The manipulation of the tool may be upon the axis of the central portion of the crank or through a circle 60 concentric with any line forming an angle with said axis. A hole 13, of relatively small diameter, is formed in and transversely of one end portion 14 of the brace. The hole 13 is employed to receive one end 65 portion of a tie wire 15 and when so used the operation of the tool and associated parts is as follows. In Figure 1 there is shown a section of a fence comprising an end post 16, intermediate posts 17, 18, strand wires 19, 70 20, 21 and 22 fixed at one end each to the end post and extending across the intermediate posts and secured thereto, the strand wires being stapled to the post 18 but tied to the post 17 because of the shattered and 75 split condition of the latter post indicating the use of ties instead of staples. Figure 1 also indicates the application of stays 23, 24 and 25 to the strand wires intermediate of the posts and the stays are arbitrarily 80 grouped as shown although in use they would be selectively arranged, usually one and not more than two stays being located between any two posts. A tie 15 is employed to connect each of the strand wires 19, 20, 85 21, 22 to the shattered post 17 and stays 23, 24, 25 and said tie is applied in any location indicated in substantially the same manner. The tie 15 is first hooked over and its hook closed upon a strand wire preferably by 90 twisting the end portion of the hook on the body of the tie. Then the tie wire is placed across the rear of an object such as the stay 23, said stay being arranged vertically and extending across all of the strand wires between the tie and strand wires and said tie wire is passed beneath the strand wire and upwardly, is threaded through the hole 13 of the brace, the end portion of the brace lying on and extending across the strand 95 wire 20 adjacent to the stay and on the opposite side of the stay from the initial hook of the tie wire. Then the brace is rotated manually to the right and a portion of the tie wire is wound on the portion 14 of the brace 100 to the end and for the purpose of tightening the tie in embracing relation with the stay. This done the entire brace is revolved around the strand wire 20 starting upwardly 105 at its outer end and at the same time is 110 gradually rotated reversely to its first rotation to the end of unwinding the tie wire

from the portion 14. This operation is gradual and is performed with some knack and skill on the part of the operator to the end that the otherwise free portion of the tie wire may be coiled rigidly and compactly upon the strand wire without slackening the stretching and embracing relation thereof. This operation is repeated in the application of any tie wire 15 for the connection of any strand wire to any upright device such as a stay or post.

A slot 26 is formed in the portion 14 of the brace between the hole 13 and crank 10 and said slot preferably is centrally and longitudinally arranged. This slot is of relatively small width and is intended to accomodate two or more wires side by side, and the slot is employed in preference to a hole because of the greater strength the use of a slot permits in the brace. The brace is employed in respect of the slot 26 as follows. Between the posts 17 and 18 in Figure 1 each of the strand wires 19, 20, 21, 22 is shown broken, the first or uppermost wire showing a simple break. To repair this break through the use of my tool loops 27, 28 are formed in adjacent end portions of the strand wire, a splice wire 29 is doubled on its center and passed through the loop 27 singly and through the loop 28 doubly, the end portions of the splice wire extending upwardly through the latter loop. The end portions of the splice wire are passed upwardly through the slot 26, the portion 14 of the brace extending across and resting on the loop 28 as illustrated in respect of the strand wire 22. Thereupon the brace is rotated manually to the right as indicated by the arrow in Figure 1 and portions of the splice wire 29 are wound on the portion 14 of the brace to the end of stretching and tightening the strand wire through the medium of the splice wire. When the desired tension is attained the loop 28 is grasped, engaged and held by a suitable tool such as pliers and the brace is revolved around the body of the splice wire 29 and during such movement the body of the splice wire lies in a plane oblique to the plane of the circumference of the circle through which the brace is moved. At the same time the brace is rotated reversely to the direction indicated by the arrow in Figure 1 to the end of unwinding end portions of the splice wire from the portion 14 of the brace. This operation is effected with knack and skill on the part of the user to the end that end portions of the splice wire may be coiled compactly on and contact firmly with the body portion of the splice wire at the left of the loop 28, and is continued until end portions of the splice wire are withdrawn from and release the brace.

It is desirable to provide some means for limiting the splice wire or stay wire longi-

tudinally of the brace and to that end a series of flanged collars 30, 31, 32 are mounted in spaced relation on the end portion 14 of the brace and secured thereto as by rivets 33. It is the function of the collar 30 to prevent coiled portions of the splice wire 29 from slipping upon the adjacent portion of the crank 10. It is the function of the collar 31 to prevent coiled portions of the tie wire 15 from departing from the location of the hole 13 in one direction and it is the primary function of the collar 32 to prevent said tie wire from slipping off the end portion of the brace.

The collar 32 has another function. It is formed with diametrical spaced holes 34, 35 in its flange. A length of wire 23' is doubled or recurved on its center and engaged with a hook such as 36 rigidly located. Then the arms of the wire 23' are extended through the holes 34, 35 as shown in Figure 5 and the brace is manually rotated to the right and withdrawn gradually longitudinally of said arms. The result of such operation is to produce a stay 23 having an eye 23'' at one end formed by the hook 36. The pitch of the coils in the stay may be regulated by more or less rapid withdrawal of the tool longitudinally of the arms of the stay wire or by engaging the extremities of said arms with the brace initially.

A flanged collar 37 may be mounted on the opposite end portion 38 of the brace 11 and secured thereto by a rivet 39. The flange of the collar 37 preferably is formed with a rim 40 substantially circular in cross-section for convenience in handling and said flange also is formed with spaced holes 41, preferably four in number arranged at equal distances of separation immediately within the rim. The collar 37 is extended outwardly beyond the end of the brace on the opposite side of the flange and is formed with a bore 42 in alignment with said end portion of the brace. Two stay wires 25' are doubled or recurved on their centers and engaged therewith at a hook 36. A core or rod 43, preferably made of metal forming a suitable electrical conductor, such as copper, is placed with one end portion contiguous to the hook 36 and the other end portion within the bore 42. The end portions of the arms of the stay wires 25' are placed through the holes 41 as shown in Figure 6 and the brace is rotated to the right, bearing and articulating on the outer end portion of the core 43 and operating to lay the arms of the stay wires in coils on said core. Thus a stay 25 is produced which is adapted to be mounted on and tied to the strand wires of a fence, one end thereof being embedded in the earth beneath the fence and the other end thereof extending above the uppermost strand wire and the whole serving as a lightning-rod or electrical conductor to relieve the strand wires of the

fence of an excessive load of electricity and tending to the safety of live stock and human beings contacting with the fence.

I claim as my invention—

- 5 1. A wire-mending and fence tool, comprising a brace formed of a single length of bar metal substantially circular in cross-section and of uniform diameter from end to end having a crank in its central portion and alining straight end portions, one of said end portions being formed with a longitudinal slot adjacent the crank and also formed with a transverse hole adjacent its extremity.
- 10 15 2. A wire-mending and fence tool, comprising a brace formed of a single length of bar metal substantially circular in cross-section and of uniform diameter from end to end, having a crank in its central portion and alining straight end portions, one of said end portions being formed with an aperture adjacent the crank and also formed with a transverse hole adjacent its extremity.
- 20 25 3. A wire-mending and fence tool, comprising a brace formed of a single length of bar metal substantially circular in cross-section and of uniform diameter from end to end, having a crank in its central portion and alining straight end portions, one of said end portions being formed with an aperture adjacent the crank and also formed with a transverse hole adjacent its extremity, said crank being formed with a longitudinal transverse slot.
- 30 35 4. A wire-mending and fence tool, comprising a brace formed of a single length of bar metal substantially circular in cross-section and of uniform diameter from end to end, having a crank in its central portion and alining straight end portions, one of said end portions being formed with an aperture adjacent the crank and also formed with a transverse hole adjacent its extremity, and spaced flanged collars mounted on said apertured end portion of the brace.
- 40 45 5. A wire-mending and fence tool, comprising a brace formed of a single length of bar metal substantially circular in cross-section and of uniform diameter from end to end, having a crank in its central portion and alining straight end portions, one of said end portions being formed with an aperture adjacent the crank and also formed with a transverse hole adjacent its extremity, and spaced flanged collars mounted on said
- 45 50 55 60 65 70 75 80 85 90 95 100 105 apertured end portion of the brace, the outermost flanged collar being formed with diametrically opposite transverse holes.
6. A wire-mending and fence tool, comprising a brace formed of a single length of bar metal substantially circular in cross-section and of uniform diameter from end to end, having a crank in its central portion and alining straight end portions, one of said end portions being formed with an aperture adjacent the crank and also formed with a transverse hole adjacent its extremity, and spaced flanged collars mounted on said apertured end portion of the brace, one of said collars being located between said aperture and the crank, one of said collars being located between said aperture and the hole, the remaining collar being located at the outermost extremity of said end portion of the brace.
7. A wire-mending and fence tool, comprising a brace formed of a single length of bar metal substantially circular in cross-section and of uniform diameter from end to end, having a crank in its central portion and alining straight end portions, one of said end portions being formed with an aperture adjacent the crank and also being formed with a transverse hole adjacent its extremity, and a flanged collar mounted on one end portion of the brace and formed with a bore projecting beyond the brace, the flange of said collar being formed with spaced transverse holes.
8. A wire-mending and fence tool, comprising a brace formed of a single length of bar metal substantially circular in cross-section and of uniform diameter from end to end, having a crank in its central portion and alining straight end portions, one of said end portions being formed with an aperture adjacent the crank and also formed with a transverse hole adjacent its extremity, and a flanged collar mounted on one end portion of the brace and formed with a bore projecting beyond the brace and adapted to journal on a rod, the flange of said collar being formed with spaced transverse holes adapted to receive a plurality of wires and, in the rotation of the brace, coil said wires around said rod.

Signed at Des Moines, in the county of Polk and State of Iowa, this 20th day of March, 1922.

BENJAMIN F. EMERY.
